UNITED STATES PATENT OFFICE.

ERNEST R. HUNTER, OF RIVERSIDE, CONNECTICUT.

AUTOMATIC MUSICAL INSTRUMENT.

1,251,233.

Specification of Letters Patent. Patented Dec. 25, 1917.

Application filed November 2, 1914. Serial No. 869,779.

To all whom it may concern:

Be it known that I, ERNEST R. HUNTER, a citizen of the United States, residing in Riverside, Fairfield county, State of Connecticut, have invented certain new and useful Improvements in Automatic Musical Instruments, of which the following is a specification, reference being had to the accompanying drawing, forming a part hereof.

10 This invention relates particularly to the means for supporting and operating, in a piano player, the music sheet by which the operation of the player is controlled and the tracker bar with which such music sheet 15 operates. In another application, filed concurrently herewith, there is set forth an improvement in perforated music sheets the purpose of which is to enable the performer to read intelligently and in accordance with 20 the principles of ordinary notation, the perforated music sheet as it passes over the tracker bar. Such improved music sheet is designed to travel in a substantially horizontal direction, from right to left, so that the music 25 thereon may be read as it is reproduced, and the perforations are also so arranged therein as to permit the employment of a tracker bar of less than the ordinary length. The present invention has for its object to provide 30 suitable means for the support and movement of such improved music sheet and an improved tracker bar for coöperation therewith. The invention will be more fully explained hereinafter with reference to the 35 accompanying drawing in which a suitable embodiment thereof is illustrated and in which—

Figure 1 is a view in front elevation showing the improved tracker bar and so much 40 of the means for supporting and moving the music sheet as is necessary to enable the invention to be understood.

Fig. 2 is a perspective view partly in section of a player piano to which the invention is applied.

Fig. 3 is a detail view showing a portion of the tracker bar and a music sheet.

The perforated music sheet *a*, as already stated and as fully set forth in the application referred to, has the perforations formed 50 therein in succession from left to right and arranged in the same relation which the notes represented bear to each other and to the lines and spaces of the musical staff, with 55 the perforations for the accidentals displaced slightly to the right with reference

to the naturals which correspond therewith in point of time. This formation of the music sheet makes it necessary for the same to travel from right to left if the music 60 thereon is to be read as it is reproduced, rather than in a substantially vertical direction as at present, and therefore requires reconstruction of the tracker box, particularly with respect to the means for supporting 65 and moving the music sheet and the tracker bar, as will be described.

The piano to which the invention may be applied, may have in its front casing *b*, the usual opening *c* through which the music 70 sheet may be applied, removed and viewed, and may be provided also with a tracker box or frame *d* substantially of usual construction, except as hereinafter indicated. The tracker bar *e*, instead of being placed 75 as usual in a horizontal position, is placed in a vertical plane, and it has the ports *e'* and *e²* formed therein in two vertical series, offset from each other in different vertical lines, the perforations *e'* which correspond 80 to the naturals of the key-board being in one line, while the perforations *e²*, which correspond to the accidentals of the key-board, are offset in another line, preferably 85 to the right. This permits the ports for the accidentals to be staggered with reference to the ports for the naturals and therefore a given number of ports, both naturals and accidentals, to be formed in a tracker bar of much less length than would be necessary if 90 all of the ports, both naturals and accidentals, were formed in a single line or series. This reduction in length of the tracker bar of course permits a corresponding reduction 95 in width of the music sheet *a*, with all the obvious advantages of reduction in cost of stock, of reduction in expansion and contraction with changes in atmospheric conditions, of reduction in liability of failure to track properly, and in increase of convenience in operation and handling. The ports 100 of the tracker bar may be connected as usual by tubes *f* with the player pneumatics of the piano, the bank of which is indicated generally at *f'*.

The spool or roll *g* upon which the perforated music sheet is supplied, may be formed in every respect as usual except for its reduced length, and is supported with its axis in a substantially vertical plane, by a 110 bearing *g'* of ordinary construction at its lower end and by a driving hub *g²* at its

upper end, the latter being driven from the motor through any suitable gearing, such as is indicated by the crown gearing h , pinion h' , shaft h^2 , sprocket h^3 and chain h^4 , from the driving sprocket h^5 . The winding-on roll i is also supported with its axis in a substantially vertical plane by bearings i' and i^2 of usual construction, and may be driven from the motor by any suitable arrangement of gearing such as the crown gear h^6 , pinion h^7 and shaft h^8 , and the driving clutch h^9 , the latter being under the control of the usual shifting mechanism represented by the lever h .

15 It will now be seen that when the music box roll g is placed in position in the tracker box, the end of the music sheet a hooked to the winding-on roll i , and the winding roll connected operatively to the motor, the music sheet will travel from right to left before the performer so that the musical notation expressed by the perforations of the music sheet may be read intelligently by the performer.

20 It will be understood, of course, that changes may be made in the details of construction and operation as may be deemed desirable by different manufacturers or for different pianos and that the invention is not limited to the precise construction shown and described herein. It will also be understood that the improved tracker box may be manufactured and sold as an article of

manufacture, ready for installation in player pianos, as well as embodied in the construction of new player pianos.

I claim as my invention:—

1. A tracker bar having the ports which correspond to the naturals of the key-board arranged in one line and the other ports arranged in another line, the ports of the two lines being relatively staggered.

2. A tracker box for automatic musical instruments having a tracker bar in a substantially vertical plane, said tracker bar having the ports which correspond to the naturals of the key board arranged in one line and the other ports arranged in another line, the ports of the two lines being relatively staggered, a winding-on roll with its axis in a substantially vertical plane at one side of the tracker bar, a perforated music sheet movable horizontally and having perforations arranged so as to bear the same relation to one another as the notes represented bear to each other and to the lines and spaces of the musical staff, and bearings for the music roll with their axes in a substantially vertical plane at the other side of the tracker bar.

This specification signed and witnessed this 30th day of October A. D., 1914.

ERNEST R. HUNTER.
